INVENTOR

Charles J. Pilliod,
By C. W. C. & C.
His atty.

UNITED STATES PATENT OFFICE.

CHARLES J. PILLIOD, OF TOLEDO, OHIO, ASSIGNOR TO DANIEL SEARLES, TRUSTEE, OF
TOLEDO, OHIO.

FURNACE-DOOR-OPERATING MEANS.

Application filed February 10, 1921. Serial No. 443,744.

To all whom it may concern:

Be it known that I, CHARLES J. PILLIOD, a citizen of the United States, and a resident of Toledo, in the county of Lucas and State 5 of Ohio, have invented a certain new and useful Furnace-Door-Operating Means; and I do hereby declare the following to be a full, clear, and exact description of the invention, such as will enable others skilled 10 in the art to which it appertains to make and use the same, reference being had to the accompanying drawings and to the characters of reference marked thereon, which form a part of this specification.

15 This invention relates to mechanisms for opening and closing the fire doors of furnaces, and more particularly to those adapted for use in connection with fire doors of locomotives.

20 The object of my invention is the provision in combination with doors of the swinging type, of a simple, efficient and improved mechanism for opening and closing the same and adapted to lock the doors in open position.

25 A further object of the invention is to provide a simple link operating means for the doors which has an action similar to the gear segment operating means commonly employed in doors of this type.

The invention is fully described in the following specification, and while, in its broader aspect, it is capable of embodiment in numerous forms, a preferred embodiment 35 thereof is illustrated in the accompanying drawings, in which—

Figure 1 is a front elevation of a furnace door mechanism embodying the invention with the connected doors in closed position. 40 Fig. 2 is a vertical section thereof on the line 2—2 in Fig. 1, with parts in full, and Fig. 3 is a fragmentary front elevation with the doors in full open position and locked in such position.

45 Referring to the drawings, 1 designates a furnace door frame having a fire-door opening 2 therein, which is closed by a pair of swinging doors 3. These doors are pivotally suspended from respective pivot studs 50 4 and 4^a for opposed opening and closing swinging movements, the studs projecting forward from the frame 1 above the opening 2 therein and in transverse horizontally spaced relation to each other. For this purpose each door 3 has an arm 5 extending

upward therefrom with one mounted on a pivot stud 4 and the other on a pivot stud 4^a. Each arm 5 is of angled form with the pivot stud bearing in its elbow portion, and one has its forearm 6 projecting inwardly 60 therefrom toward the pivot stud of the other, while the other arm 5 has its forearm 7 projecting inwardly and upwardly therefrom over the adjacent inner end portion of the arm 6 in lapping relation thereto, 65 as shown in Fig. 1. The forearm 6 carries a pivot pin 8 at its free end and the forearm 7 carries a pivot pin 9 at its free end, and these pins are connected by one or more links 10 whereby the doors are tied together and caused to have opposed movements in unison whenever one is moved.

A fluid operating means for the doors may be employed and in the embodiment thereof illustrated in the drawings, 11 designates 75 a cylinder having a piston therein with its piston-rod 12 connected to a pivot pin 13 on the arm 5 of one of the doors, the cylinder being carried by the frame 1 in horizontal position. A suitable valve mechanism 14 for controlling the admission of fluid to and from the cylinder 11 is provided and operated from a foot pedal 15 through any suitable intermediate connection, as well understood in the art.

In order that the doors may be manually operated when desired, a control lever 16 is provided for such purpose and is fulcrumed on a stud 17 projecting from the frame 1 above the forearm 6. The short 90 arm 18 of this lever extends from the lever fulcrum over the hub portion 19 at the lower end of one of the links 10 in position to bear downward on such hub portion and impart an opening movement to the doors 95 when the lever is thrown down from the position shown in Fig. 1 to that shown in Fig. 3. When the doors are in full open position the lever-arm 18 is in end abutment with the link hub 19 to lock the doors against gravity closing movements, as shown in Fig. 3.

One of the primary objects of the present invention is to provide a simple link connecting means for furnace doors of the class 105 described, whereby the action thereof will be similar to the action of gear segments customarily employed to impart opening and closing movements in unison to the doors, thereby giving a better mechanical con- 110

struction and eliminating the liability of breakage which is present when a gear toothed structure is employed. With the arrangement shown the pivots 4, 8 and 4^a are in horizontal alignment when the doors are in closed position, as shown in Fig. 1, and the pivots, 4, 9 and 4^a are in horizontal alignment when the doors are in full open position. It will also be noted particularly 10 by reference to Fig. 3 that a straight line will pass through three points determined by the centers of the pivots 8 and 9 when in closed position and by the center point of the pivot 8 when at the limit of its lower throw, thereby causing the action of the forearm and link connection between the arms 5, 5 of the doors to be the same as the action of connected gear segments between said arms.

I wish it understood that my invention 20 is not limited to any specific construction, arrangement, or form of the parts, as it is capable of numerous modifications and changes without departing from the spirit of the claims.

25 Having thus described my invention, what I claim as new and desire to secure by Letters Patent, is,—

1. In combination, a furnace door frame having an opening therein, a pair of doors 30 pivotally suspended from the frame for opposed opening and closing movements, the door pivots being transversely separated in a common horizontal plane, one door having an arm projecting from its inner end toward the pivot of the other door when the doors are in closed position, and the other door having an arm projecting inward therefrom over the first arm, a link connecting said arms with the pivots thereof when in 35 closed position disposed substantially in a straight line with the positions which the pivots assume when in open position, and means for imparting opening movements to the doors.

45 2. In combination, a furnace door frame having an opening therein, a pair of trans-

versely spaced pivot studs projecting in a common horizontal plane from the frame over its opening, a door swingingly suspended from each pivot, said doors having arms extending inward in lapping relation one over the other, a single link connecting said arms to cause the doors to have opposed opening and closing movements in unison, and an operating lever fulcrumed to the frame 55 above the doors and operable to exert a downward thrust on one arm and movable to impart opening movements to the doors, the lever adapted to have end thrust engagement with the engaged part when the arms 60 are in open position to lock them in such position.

3. In combination, a furnace door frame having an opening therein, a pair of transversely spaced pivot studs projecting in a 65 common horizontal plane from the frame over its opening, a door swingingly suspended from each stud for opposed swinging movements transverse to the frame, each door having an angled arm projecting upward 70 from its upper end and pivotally carried at its elbow portion by a respective stud and having its forearm portion projecting inward from the stud with the forearm portion of one arm lapping that of the other 75 arm, a short link pivotally connecting the free ends of the elbow portions of the arms and having a pivot receiving boss projecting laterally from its lower end, the link pivots being disposed in vertically spaced 80 relation with one offset horizontally only a short distance from the vertical plane of the other, and a lever pivoted for vertical rocking movements to the door frame above the horizontal plane of the pivot studs and 85 having a part for bearing against the boss of the link to impart an opening movement to the doors when the lever is moved in one direction.

In testimony whereof, I have hereunto signed my name to this specification.

CHARLES J. PILLIOD.
